US00D479225S

(12) **United States Design Patent** (10) Patent No.: **US D479,225 S**
De Saulles (45) Date of Patent: ** Sep. 2, 2003

(54) **HAND HELD CONTROL DEVICE**

(75) Inventor: **Stephen De Saulles**, London (GB)

(73) Assignee: **Patientline, plc**, Slough (GB)

(**) Term: **14 Years**

(21) Appl. No.: **29/148,273**

(22) Filed: **Sep. 15, 2001**

(30) **Foreign Application Priority Data**

Mar. 16, 2001 (GB) 2100364

(51) **LOC (7) Cl.** **14-03**

(52) **U.S. Cl.** **D14/218**

(57) **CLAIM**

I claim the ornamental design for a hand held control device, as shown and described.

DESCRIPTION

FIG. 1 is a perspective view thereof;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

1 Claim, 2 Drawing Sheets
